UNITED STATES PATENT OFFICE.

CHARLES A. MEUNIER, OF GREAT NECK, NEW YORK, ASSIGNOR TO CAM MANUFACTURING COMPANY, INC., OF GREAT NECK, NEW YORK, A CORPORATION OF NEW YORK.

DESIGN FOR AN END CAP FOR EAVES TROUGHS.

Application filed February 1, 1927. Serial No. 20,572. Term of patent 14 years.

To all whom it may concern:

Be it known that I, CHARLES A. MEUNIER, a citizen of the United States of America, and a resident of Great Neck, in the county of Nassau and State of New York, have invented a new, original, and ornamental Design for End Cap for Eaves Troughs, of which the following is a specification.

Reference is to be had to the accompanying drawing, in which Figure 1 is a per-

spective view of an end cap for eaves troughs showing the new design and illustrating in broken lines a portion of the gutter or trough to which the same is applied; and Fig. 2 is a similar view taken from the rear of the cap.

What is claimed is—

The ornamental design for an end cap for eaves troughs as shown.

CHARLES A. MEUNIER.
